UNITED STATES PATENT OFFICE.

OLIVER E. BECKER, OF CHICAGO, ILLINOIS, ASSIGNOR TO BECKER BROS., OF CHICAGO, ILLINOIS, A CORPORATION OF ILLINOIS.

BRUSH FOR ELECTRICAL APPARATUS AND METHOD OF MAKING SAME.

Application filed November 7, 1921. Serial No. 513,245.

To all whom it may concern:

Be it known that I, OLIVER E. BECKER, a citizen of the United States, residing at Chicago, in the county of Cook and State of Illinois, have invented a certain new and useful Improvement in Brushes for Electrical Apparatus and Methods of Making Same, of which the following is a full, clear, concise, and exact description, reference being had to the accompanying drawings forming a part of this specification.

My invention relates to brushes for electrical apparatus and method of making same.

15 In conveying current to or from an armature or other moving member, for example, the circuit is through a relatively stationary terminal, such as a brush having electrical contact with a relatively moving terminal or surface, such as a commutator, collector ring, or the like. Flexible leaders or pig tails are usually employed to carry the current between the brush and the cables or other conductors employed for conveying current to the apparatus.

20 The successful operation of electrical machinery of this class is dependent largely upon the electrical connection provided between the leaders or pig tails and the relatively stationary terminal or brush and the electrical contact maintained between the relatively stationary and movable terminals.

25 In my co-pending application, Serial No. 483,207, filed July 8, 1921, I have disclosed a leader or pig tail adapted to be threaded or otherwise inserted into the body of the brush. The outer end of the terminal sleeve, disclosed in the above application, is provided with a non-circular portion for 30 engagement by a wrench or other suitable tool. The connection disclosed in my above application is an improvement upon, provides better electrical contact and otherwise functions more satisfactorily than the prior art provisions. However, I find that in 35 some instances, engagement of that portion of the terminal sleeve beyond the threads formed therein, with the brush, upon forcing the terminal into place, distorts the connection between the pig tail and the brush and impairs the electrical contact therebetween. This is particularly so where there

is any unevenness or other irregularity in such surfaces.

My present invention overcomes any possibility of such difficulty by the provision of an improved lead construction and method of making the same and an improved connection between it and the brush body.

40 A further feature of my present invention is the provision of an improved facing piece engageable by the means provided for pressing the brush into contact with the commutator, slip ring or the like and an improved arrangement and mounting thereof.

45 Still further features of my invention are the provision of means for still further improving the electrical contact between the brush or contact piece and the lead or pig tail; for lubricating the connection between the lead and contact piece, and for preventing oxidation and keeping the co-operating contact surfaces clean.

50 The result of these features, together with certain constructural details and such other features as will appear from the following detailed description is a novel, simple and improved brush having structural superiority, manufacturing economy and functional advantage over the brushes of the prior art.

55 In order to more fully acquaint those skilled in the art with the nature of my invention, I shall now describe, with the aid of the accompanying drawings, the steps which I perform and the structure of the brush secured thereby.

In the drawings:

Figure 1 is an elevational view of the pig tail;

Figure 2 is an elevational view of the terminal sleeve or ferrule;

Figure 3 is an elevational view of the pig tail showing the sleeve or ferrule secured thereupon and the faces formed in the ferrule for engagement by a wrench or other suitable tool;

Figure 4 is an elevational view of the finished pig tail;

Figure 5 is a horizontal sectional view taken substantially on the line 5—5 of Figure 4;

Figures 6, 7, 8 and 9 are isometric views of the brush body, pig tail, facing clip and

the pin for securing the pig tail in the brush body respectively;

Figure 10 is an isometric view of the finished brush;

5 Figure 11 is an isometric view of a brush holder showing a brush embodying my invention mounted therein; and

10 Figure 12 is an enlarged transverse sectional view showing the manner in which the electrical contact between the contact piece and lead may be still further improved, the connection therebetween lubricated; oxidation prevented and the cooperating contact surfaces kept clean.

15 According to my invention, the end of the pig tail 10 is inserted in the sleeve or ferrule 11 and union between the sleeve and pig tail then produced by deforming the sleeve as by crushing or pressing it inwardly to a smaller diameter between suitable dies to compress the fibres of the pig tail and firmly grip them in the sleeve. The outer end of the sleeve 11 is pressed, crushed or otherwise formed into a non-circular shape, so that it may be engaged by a wrench or other suitable tool. In the particular embodiment selected for illustration, this end is shown at 12 as being formed square. It may be formed with any desired number of faces. The faces 12 may be formed simultaneous with the effecting of the gripping action or union between the sleeve 11 and pig tail 10, or they may be formed in independent steps if so desired. It should be noted, however, (Fig. 5) that the periphery of the squared end 12 is confined wholly within the diameter of the lower portion 13 of the sleeve or ferrule.

40 Screw threads 14 are then formed preferably throughout the length of the sleeve 11 as shown, continuing up through the corners 15 of the squared end 12 of the sleeve. Should the end 12 be squared to a dimension within the internal diameter of the threads 14, the threads will, of course, not take in the corners 15. The threads 14 are preferably formed by rolling as in my co-pending application, not only because such a method is cheaper, but because such method of forming the threads tends to increase rather than decrease the gripping action or union between the sleeve and the strands of the pig tail. While the end 55 of the sleeve 11 is preferably squared first and the screw threads 14 then formed therein as described, it is to be understood that these steps in forming the pig tail may be reversed and the sleeve 11 threaded first and one end then squared without departing from my present invention.

The threads formed should preferably be sharp 60° threads to secure a large contact area with the material of the brush.

60 65 The threaded end of the sleeve or ferrule

of the finished pig tail is then screwed into an opening 16 in the brush body 17. While the particular brush shown is of the rigid granular type composed usually of a carbon base, such as graphite or coke mixed with other ingredients to impart structural strength and good wearing qualities, it is to be understood that my present invention is not limited to any particular type of brush. The opening 16 in the brush body 17 may be tapped as shown, or the inner end of the sleeve 11 may be fluted and thereby screwed into the opening 16 without tapping the same as described in my co-pending application. In either event, the connection established between the pig tail and the brush possesses the mechanical requirements of strength and durability and the electrical requirement as to firm contact over a large area is maintained, even after prolonged service. It should be noted that the pig tail may be screwed completely and securely into the brush without in the least impairing the firm contact between the threads on the sleeve 11 and those in the opening 16, such as might happen under certain conditions where the insertion of the pig tail is limited by engagement of a shoulder or enlarged portion on the sleeve 11 with the brush body.

Upon complete insertion of the pig tail, an opening is drilled or otherwise formed transversely through the brush body 17, sleeve 11 and the end of the pig tail strands secured therein and a pin 18 is then inserted through this opening and riveted or headed over at its opposite ends to securely bind the pig tail and its terminal sleeve in the body of the brush.

Intermediate the opposite ends of its upper edges, each of the opposite faces of the brush body 17 is scarfed or notched as shown at 19 to receive the downwardly converging flaps or ears 20 of a facing clip 21. The scarfs or notches 19 are under-cut as shown in Figure 6, that is, they extend deeper into the body of the brush at a point below the upper edge than they do at the upper edge. The facing clip 21 which is made up of suitable spring stock, preferably phosphor bronze is secured in place by spreading the downwardly converging flaps or ears 20 and springing them into the under-cut notches or scarfs 19 as shown in Fig. 10. When so positioned, that portion of the clip 21 connecting the flaps 20 extends transversely across the upper surface of the brush body providing an admirable facing surface engageable by the means provided for pressing the brush into contact with the commutator or slip ring.

The facing clip 21, particularly the under surface which comes into direct engagement with the brush body, is provided with a suitable insulating coating. I find that two

coats of "japan" provides a highly satisfactory coating for this purpose. Instead of coating the facing piece a layer of paper or other suitable insulation may be arranged 5 between it and the brush body 17. In either case, the pig tail makes direct electrical contact with the brush body entirely independent of the mechanical connection provided between the facing piece and the 10 brush. Consequently, the variable electrical contact and accompanying variable resistances heretofore encountered, especially where the mechanical connection between the facing piece and brush has served as the 15 electrical connection between the leader or pig tail and the brush are avoided, and a constant contact resistance is provided. Furthermore, there is no possibility of a flow of current being set up to the brush 20 through the arm provided for pressing the brush into contact with the commutator or slip ring and facing piece engaged thereby as has been possible heretofore, especially where the leader or pig tail has been electrically connected at one end with the facing 25 piece at the brush and at its opposite end with a metallic arm or terminal carrying the spring pressed arm.

In Fig. 11, I have illustrated the manner 30 in which a brush embodying my invention may be mounted in the usual brush holder employed in apparatus with which such brushes are adapted for use. The details of the holder per se are, of course, immaterial 35 in so far as my present invention is concerned, and will vary in different machines. The particular holder shown comprises an open rectangular frame 25 having an arm 26 terminating at its free end in a clamping 40 jaw 27. The arm 26 carries a plate 28 having upturned bearings 29 which support a shaft 30. One bearing is provided with a plurality of ratchet teeth for engaging the end 32 of a spring 33 coiled about the shaft 45 30. The other end 35 of the spring 33 engages ratchet teeth formed on the hub of a swinging arm 34. The arm 34 is freely rotatable on the shaft 30 and being secured to the end 35 of the spring 33, the outer 50 end of the arm is pressed against that portion of the facing piece 21 extending across the top of the brush 17 with a degree of tension varying on the setting of the spring. The brush is pressed down by the arm 34 55 with a degree of tension sufficient to cause good contact between the brush and collector ring or commutator.

The elimination of an enlarged portion 60 beyond the threads formed in the terminal sleeve insures proper electrical contact regardless of how securely the terminal is forced into place. Threading of the sleeve is also facilitated.

In Figure 12 I have shown the manner in 65 which the electrical contact between the con-

tact piece and lead may be still further improved, the connection therebetween lubricated, oxidation prevented and the cooperating contact surfaces kept clean. In this case the opening 16' in the contact piece or brush body 17' is tapped to receive the threaded end 14' of the lead 10'. The tapped opening 16' is filled about two-thirds full of a conducting powder 50 preferably "Ceylon" graphite. The threaded end 14' of the lead is that inserted into the opening 16' and engaged with the threads therein whereupon the brush body or contact piece is turned upside down and the lead then screwed up into place. I find that the conducting powder 50 not only lubricates the cooperating threads between the contact piece and lead, prevents oxidation and keeps the cooperating contact surfaces clean, but that it forms a cushion mechanically between the lead and brush and forms an exceedingly good bottom contact between the end of the lead and the bottom of the opening 16'. The conducting powder upon being compressed between the end of the lead and the bottom of the opening yields sufficiently to permit good electrical contact being made therethrough without distorting the contact between the cooperating threads and impairing the flow of current therebetween.

While I have described my invention in connection with a brush, it is obvious that the invention may be practiced in connection with various other contact members than the one shown, whether or not such contacts are included under the term "brushes".

I do not intend to be limited to the precise details shown and described, and I intend that modification in the order of practicing the various steps such as will be apparent at once to those skilled in the art are contemplated within the scope of the appended claims.

I claim:

1. The method of forming a pig tail which comprises, inserting a pig tail strand in a sleeve or ferrule, forming a non-circular portion in the sleeve or ferrule and forming threads in the ferrule past said non-circular portion.

2. The method of forming a pig tail which comprises, inserting a pig tail strand in a sleeve or ferrule and then forming threads and a non-circular portion in the thread receiving length of the ferrule in successive steps.

3. The method of forming a pig tail which comprises inserting a pig tail strand in a sleeve or ferrule, then deforming the material of the sleeve to force it into secure engagement with the strand and then forming threads in the sleeve throughout its length.

4. In combination, a stranded conductor, a cylindrical sleeve permanently shrunk up on one end of the conductor, said sleeve hav-

- ing its outer end threaded and its inner end of non-circular formation for engagement by a suitable wrench and confined within the peripheral dimension of the threaded outer end.
5. In combination, a conductor, a sleeve permanently shrunk upon one end of the conductor, said sleeve being threaded and having a non-circular portion confined within the peripheral dimension of the thread, and adapted for engagement by a suitable tool.
6. In combination, a stranded conductor, a cylindrical sleeve shrunk upon one end of the conductor, said sleeve having a threaded portion and a non-circular portion having a peripheral dimension less than that of the threaded portion for engagement by a suitable tool.
7. In combination, a conductor, and a sleeve shrunk on the end of the conductor, said sleeve having a non-circular portion for engagement by a suitable tool and being threaded past said non-circular portion.
8. In combination, a brush body having a hole extending into but not through the body thereof, a conductor having a sleeve of metal secured upon its end, said sleeved end being threaded into said hole and means interposed between the sleeved end of the conductor and the bottom of said hole for bottoming the conductor in the hole.
9. In combination, a brush body having a hole extending into but not through the body thereof, a conductor secured in said hole and a conducting powder interposed between the end of the conductor and the bottom of said hole and bottoming the conductor therein.
10. In combination, a brush body having a hole extending into but not through the body thereof, a stranded conductor, a connecting sleeve permanently shrunk upon the stranded conductor and threaded for engagement in the brush body, a conducting powder interposed between the end of the conductor and the bottom of the hole, and a retention element engaging the brush body and the sleeved end of the conductor for holding the same against unthreading.
11. The method of connecting a lead mechanically and electrically to a brush body which comprises, shrinking a sleeve permanently upon the end of the lead, forming threads upon said sleeve, forming an opening in the brush body, introducing a conducting powder into said opening, and threading the sleeved end of the lead into the opening and bottoming same on said powder.

In witness whereof, I hereunto subscribe my name this 4th day of November, 1921.

OLIVER E. BECKER.
